INVENTOR:

George R. Howe

UNITED STATES PATENT OFFICE.

GEORGE R. HOWE, OF NEWARK, NEW JERSEY.

BUTTON.

SPECIFICATION forming part of Letters Patent No. 242,202, dated May 31, 1881.

Application filed April 28, 1881. (No model.)

To all whom it may concern:

Be it known that I, GEORGE R. HOWE, a citizen of the United States, residing at Newark, in the county of Essex and State of New Jersey, have invented certain new and useful Improvements in Buttons, of which the following, taken in connection with the accompanying drawings, is a full, clear, and concise description of the nature and character of my invention, so that any person familiar with the art may make, construct, and use the same.

My improvement relates to that class of buttons and studs in which the shoe is pivoted to the post; and it consists in a novel method of 15 constructing the post and shoe, as will be hereinafter fully described.

Referring to the drawings, which are drawn on an enlarged scale, Figure 1 is an elevation of the button, with the shoe in position when 20 applied. Fig. 2 is a vertical section on line $x-x$, Fig. 1. Fig. 3 is an elevation of the button, with the shoe in plan, turned up against the shank, in position to be inserted in the button-hole. Fig. 4 is a view, similar to Fig. 3, of a 25 modification; and Fig. 5 is a plan of the shoe and lug.

The same letters of reference indicate corresponding parts in all of the figures.

A represents the head or face of the button, 30 which may be of any desired form, and may be of metal, or with stone or other setting, to suit the taste or fancy of the wearer.

B represents the shoe or back disk.

C is the post or shank.

35 a is a short post or lug secured to the center of the shoe, and b is the pintle, by means of which the shoe and its lug are pivoted to the post or shank of the button. The post or shank is bifurcated, and consists of two legs or arms 40 of semi-tubular metal, with their concave or hollow portions inside or toward a line drawn vertically through the center of the button. This two-part shank is made of spring metal, for a purpose which will presently appear, and 45 the lower ends of the legs are perforated to receive the pintle which pivots them to the shoe. The bifurcated post is secured to the button-head by soldering, riveting, or in any other suitable manner.

50 The shoe proper is of the ordinary form, and consists of a convexo-concave disk of metal;

but to the center of its concave or inner side is secured a short lug with cam-shaped edges. This lug is perforated near the top or upper end for the passage of the pintle b, which pivots it to the bifurcated post. The lug is substantially a parallelogram in cross-section; but its vertical edges are shaped to fit the internal concave portions of the bifurcated post, and when the shoe is in position, or at a right angle to the post, is exactly the width of the space between the legs of the posts. The shoe and lug are pivoted to the post by inserting the pintle b through the perforations in both of the parts.

55 In Fig. 4 I have shown a modification of my improvement, in which the bifurcated post is made of round instead of semi-tubular wire or metal, and the lug on the shoe is made with concave vertical sides or edges to fit the round wire, instead of the convex sides to fit the concave legs of the post, as shown in the other figures. In both instances the sides of the lug on the shoe are made of a form corresponding 60 with the form of the legs of the shank, and a 65 separate spring is entirely dispensed with. I also sometimes form the post or shank by taking a button having the ordinary tubular shank and making a vertical slot or saw-cut therein; but I prefer the form first described, as it requires less metal, which is a valuable consideration 70 where precious metals are used, and I 75 find it sufficiently strong for all practical purposes.

80 The operation of my button will be apparent. 85 The shoe, with its cam-shaped lug, can be turned nearly in line with the shank, and by my construction may be turned to either one side or the other. Like all buttons of this class, it may then be readily inserted in the button-hole.

85 It will be seen that when the shoe is turned up against the side of the shank the two legs of the latter are sprung slightly apart, as shown in full and dotted lines in the drawings, by 90 the action of the cam-shaped lug on the shoe, and when the shoe is again turned a quarter revolution the legs of the post assume their normal position and, embracing the cam-shaped 95 sides of the lug, hold the shoe firmly in position. 100

By my invention I am enabled to produce a very cheap and durable button, and one that

has no intricate mechanism for pivoting the shoe, and therefore very easily constructed. Having thus fully described my improvement, what I claim as new, and desire to secure by Letters Patent, is—

1. A button or stud provided with a bifurcated spring-shank, and a shoe having a lug with cam-shaped sides, corresponding with the form of the legs of the shank, pivoted thereto, and adapted to be operated substantially in the manner and for the purpose specified.

2. A button or stud having a suitable head, a semi-tubular bifurcated spring-shank, and a

shoe having a cam-shaped lug, the shoe and lug pivoted to the shank, as set forth.

3. A button or stud provided with a bifurcated spring-shank, and a shoe having a lug or projection with cam-shaped sides corresponding in form to the legs of the shank and pivoted thereto, and adapted to be locked in its normal position by the inherent spring of the shank, substantially as specified.

GEORGE R. HOWE.
